UNITED STATES PATENT OFFICE.

ALEXANDER CRAWFORD CHENOWETH, OF NEW YORK, N. Y.; CATHARINE R. CHENOWETH ADMINISTRATRIX OF SAID ALEXANDER CRAWFORD CHENOWETH, DECEASED.

METHOD OF AND APPARATUS FOR LAYING PROTECTING COVERINGS.

Application filed March 16, 1917. Serial No. 155,197.

My invention relates to protective work, and my improvements pertain more particularly to laying protective coverings or slabs, either in green, unset condition, or in dried and hardened condition, upon the surface to be protected, such as for example, the bed or bank of a body of water, or the floor for a break-water, or the formation of a retaining wall or slope.

10 I have illustrated types of my invention in the accompanying drawings, wherein;

Fig. 1 is a top plan view of the apparatus with the forming-barge shown as standing part way in the space between the two floats 15 at one end of the same and with the slab omitted.

Fig. 2 is a side view of the apparatus shown as floating upon the surface of a body of water with a finished slab upon the forming barge and connected up with the hoisting-tackle ready to be lifted from the barge, which is subsequently withdrawn from beneath the slab. The dotted lines in this figure indicate the parts of the two floats and 25 the barge, which extend beneath the surface of the water.

Fig. 3 is an enlarged perspective view of a portion of a completely finished slab with the bent wire-mesh reinforce, the slab being 30 shown as resting upon the deck of the forming barge, with a part broken away.

Fig. 4 is an enlarged vertical sectional view of a portion of a slab together with a portion of the hoisting tackle with its 35 leasing device.

Fig. 5 is a vertical sectional view of the apparatus and shows the relative positions of the different parts after the slab has been lifted from the forming-barge and the latter withdrawn from beneath the slab, which is shown as being lowered at an angle to the horizontal with the inner end of the slab resting upon the bank to which it is anchored, and the outer end extending into the 45 water and being gradually lowered onto the bed of the body of water.

Fig. 6 is a transverse vertical section of the apparatus as shown in Fig. 1, with a finished slab in place upon the forming-barge ready to be lifted from it by the hoisting-tackle.

Fig. 7 is a vertical sectional view of a slightly modified form of the apparatus in which the graduated set of driving-gears,

of the winding drums for the hoisting 55 tackle, is omitted; and a single set of uniform sized gears are used in order to lower the slab horizontally, and which form may be used more especially for laying a concrete slab in green, unset condition. 60

Referring to the drawings, in which like numbers of reference designate like parts throughout, 1 and 2, indicate two floating platforms or pontoons, arranged in parallel relation opposite each other and upon which 65 is erected the superstructure 3, the said parts constituting a very substantial mechanism on the order of a catamaran. The superstructure 3, is constructed of suitable truss-work and spans the space between the twin 70 platforms, and the structure is made of sufficient strength to perform the work required of it; namely, to support through means of suitable hoisting mechanism, the entire weight of the completed revetment 75 covering or slab 4, when the same is bodily lifted from the construction or forming-barge 5, and lowered into place, the barge 5, being of sufficient length to accommodate the particular length of slab that is being 80 used, and being adapted to fit easily in between the twin platforms 1 and 2, from which place it may be withdrawn.

On the float 1, I mount a suitable hoisting apparatus 6, on the main shaft 7, of which 85 is a sprocket-wheel 8, over which passes a chain 9, the chain passing around another sprocket 10, on the counter-shaft 11, which is mounted transversely of the apparatus on suitable bearings fixed on the uppermost 90 longitudinal members 12, of the structure. A series of transverse winding-shafts 13, 14, 15, 16, 17, 18, and 19, are mounted below the level of the shaft 11, and in parallel relation therewith in suitable bearings on other 95 longitudinal members of the structure, and these shafts are respectively provided with sprocket-wheels 20, 21, 22, 23, 24, 25, and 26, which are engaged respectively by sprocket-chains 27, 28, 29, 30, 31, 32, and 33, 100 which are driven from the shaft 11, through means of the respective sprockets 34, 35, 36, 37, 38, 39 and 40. The winding shafts 13 to 19, inclusive, are provided with clutches 41, 42, 43, 44, 45, 46, and 47, respectively (see 105 Fig. 1) each of which is operated by the usual pivoted forked lever, one of which, 48, is shown in the view in Fig. 6, in which the

clutch 42, is shown as controlling the sprocket 21. This clutch is so constructed that when closed the sprocket-wheel drives its shaft, but when open the shaft remains at rest.

Each of the counter-shafts is provided with several winding drums 49, which are spaced a suitable distance apart, and each drum is provided with a hoisting-cable 50, which passes through a pulley block 51, thence upwardly to a block 52, secured to a fixed point on the super-structure, and thence downwardly to a point 53, on the pulley-block 51. This form of hoisting-tackle is placed at sufficient intervals on each of the counter-shafts to suspend with ample margin of safety the completed concrete slab 4. In the present construction I show a series of four of such tackle on each counter-shaft, 10 and there are seven counter-shafts, but of course the number of these may be varied to suit the conditions required in particular cases. By this arrangement it will be seen that when all of the clutches on the various 20 counter-shafts are closed and the hoisting engine is in operation, each of the tackle devices will be operated in a similar manner to raise or lower the slab suspended thereby, and as it is desirable at times to make 30 idle some of the tackle, this may be done in gangs by stopping the motion of a particular counter-shaft by opening the clutch hereinbefore described.

When the forming barge 5, has been 35 brought into position between the two floats, as indicated for instance, in Fig. 2, with the bow of the barge projecting somewhat beyond the floats, the work of laying the slab may be started above the high-water mark 40 on the bank 56, and carried thence down along the river bed 57, the body of water being indicated at 58. The reinforced concrete slab 4, may be constructed directly on the barge after the manner indicated in 45 Figs. 2, 3, 4, and 6, by first placing on the deck of the barge a layer of wire-mesh 60, of suitable gauge for the purpose required, a mesh eight or twelve inches square being suitable under some conditions, and over this 50 is laid a piece of burlaps 61, or other suitable fabric, and a sheet of wire-mesh 62, bent in parallel ridges showing in cross section a Z-shaped figure as indicated in Figs. 3, and 4, and then the wet concrete 63 is placed 55 upon the bent wire-mesh and packed upon it and levelled off so as to completely embed the mesh, the depth of the concrete being four inches though this dimension may, of course, be varied. The bottom layer 60, of 60 wire-mesh, is used as a lifting means or cradle and attached to it are a series of lifting-eyes 64, the stems of which are sufficiently long to pass through the body of concrete so that the eyes appear clear above 65 the upper surface of the slab as indicated

more particularly in Figs. 3, and 4. These eyes 64, are adapted to be engaged by a releasable hook 65, hanging from a cable 66, which is attached to the pulley block 51, of the hoisting-tackle. Each hook is provided with a pivoted beak 67, which is locked in closed position, by means of a pivoted link 68, pivoted on the stem of the hook 65, and this link has attached to it a pull cord 69 (see Figs. 2 and 4), which runs to a point on the super-structure from where it may be operated to release the link from the beak of the hook in order to detach it from the eye 64, and this is done when the slab is deposited and is to be disconnected from the 70 hoisting tackle.

In the hoisting-tackle thus far described, the several winding-shafts are to be driven at the same speed, and when employed to lower the slab, the latter will descend in 75 horizontal position. In order, however, to lower the slab in a position inclined to the surface of the water, as indicated in Fig. 5, I provide additional devices as follows:

On the counter-shaft 11, is mounted a second set of sprocket-wheels 70, to 76, inclusive, which drive the belts 77, to 83, respectively, and these belts in turn drive the respective sprockets 84, 85, 86, 87, 88, 89, and 90, which are mounted loosely on the respective winding-shafts 15, 13, 14, 16, 17, 18, and 19. The sprockets 85, to 90, inclusive, are each provided with a clutch 91, which when open permits the sprocket to run free on the shaft. The sprockets 85, to 90, inclusive are 90 graduated in size, the smallest one being 85, so that the winding shafts run at different speeds, the highest speed being that driven by the smallest sprocket 85. By virtue of 100 this arrangement, the slab, when lifted from the barge and the latter is withdrawn, may have one end lowered with greater speed than the other, so that the slab in its descent assumes a pronounced angle to the plane of the surface of the water, as indicated in 105 Fig. 5. This variation in the speed with which the respective ends of the slab are lowered, is utilized with slabs that have been hardened or set before being laid upon a 110 sloping or inclined surface.

At one end of the apparatus, and which may be termed the forward end or bow, I make a special construction of trussed-work of the super-structure in order to have it overhang the ends of the floats a substantial distance as indicated at 92, and some of the hoisting-tackle is mounted on this overhanging structure. This arrangement permits the apparatus to be moved close in toward the shore 56, as the adjacent end of 120 the slab is raised, so that this end of the slab can be placed well up on the shore or slope above the water line, as indicated in Fig. 5. In order to further assist in the 125 laying of slabs from a point high on the 130

shore into the water, I anchor the outer end of the slab to a fixed point 94, on the shore by means of a suitable cable 95, which may be attached to the end bar or link of the 5 series of spacing bars 96, which are loosely connected between the cables 66, which suspend the hooks 65, from the pulleys 51, of the hoisting-tackle, the respective ends of the spacing-bars 96, being provided with 10 eyes 97, through which the cables 66 pass (see Fig. 4). I also use transversely arranged spacing-bars or links 98, (see Figs. 4 and 6), which by means of eyes on the respective ends, are loosely connected with the 15 cables 66 which suspend the hooks. This arrangement of the longitudinal and transverse spacing-bars between each of the points of suspension of the slab, serves to prevent the points of suspension being made to approach each other, which action might tend 20 to buckle the suspended slab.

In laying a hardened slab from a point on the shore to a point on the bottom some distance down in the water, I rest the inner 25 end of the slab on the shore, as indicated in Fig. 5, and this serves as a fulcrum or point of support in lowering the other end of the slab into place. This method of resting or fulcruming one edge of the slab 30 on the ground relieves the apparatus of considerable of the weight of the slab, and this is an important advantage in depositing these heavy slabs on slopes. In this operation the slab revolves on its point of rest 35 as an axis of motion and this also has its advantages in handling slabs of large size and great weight. As the hoisting-tackle has each of the winding-shafts under control of a clutch, each shaft may be operated 40 independently of the other in order to adjust the angle of inclination of the slab in lowering it, and it will also be noted that while some of the winding-shafts may be operated to raise the tackle at one end of 45 the slab, the shafts at the other end may be operated to lower the tackle. This will be readily understood from Fig. 5, where it is shown that the tackle at the forward end of the slab has been operated so as to raise that 50 end, while the tackle towards the other end of the slab has been operated in the reverse manner so as to lower the slab. I also place the fixed pulleys 52, at a point on the structure between the forward end of the apparatus 55 and the winding-shaft co-operating with said pulley, and this serves to relieve the strain on the tackle as the slab swings in-shore.

As these slabs are of considerable weight, 60 the hoisting-blocks and tackle may be increased as required, and the attaching points or eyes 64, on the slab may be accordingly increased. It will be noted that these suspension eyes, in the construction which I 65 here show, are secured at their lower ends

to the wire frame or cradle 60, as indicated in Figs. 3 and 4. This arrangement provides a very strong construction and particularly in connection with the bent wire reinforce herewith shown, which in itself 70 acts to take up the stress.

In the apparatus shown in Fig. 7, the hoisting-sprockets of graduated size and their adjuncts are dispensed with and the hoisting apparatus is provided with the set 75 of uniform sized sprockets 20 to 26, inclusive, together with the various adjuncts described in connection with the other figures. This form of apparatus is used in laying reinforced concrete slabs in green, unset condition, and when they are flexible. In so using the apparatus, the slab as soon as completed and before it is set, is lifted from the forming-boat 5, by means of the hoisting-tackle described, and while suspended, the 80 forming-boat is withdrawn from beneath the slab. If the slab is to be laid well upon the shore, as indicated in Fig. 7, the apparatus is then moved in-shore, and the end of the slab adjacent is hoisted so as to clear the 85 shore until the point is reached where it is to be laid and then the end is deposited upon the shore and the lowering of the tackle deposits the slab gradually on the shore 90 95 56, and down on the water-bed, as indicated in Fig. 7, in which figure the main part of the slab is just about to be laid on the water-bed. As each of the winding-shafts is controlled by a clutch, which co-operates with the sprocket on the shaft, the different 100 parts of the slab may be raised or lowered independently of other parts, and this feature is utilized when laying the inner end of the slab well up on the shore or slope, at which time the hoisting-tackle which suspends the inner or shore end of the slab is operated independently of the other tackle. 105

The apparatus may be provided with the usual winches and hawsers for holding the apparatus in place in the water so as to 110 prevent it from moving out of place, and I show the platforms provided with winches 99, at the forward end for receiving hawsers 100, while at the other end of the platforms are arranged winches 101, for receiving the 115 hawsers 102, which co-operate with the winches 103, on the forming-boat 5.

The hoisting engine 6, which I have shown herewith, is of an ordinary well-known construction and is provided with the usual 120 clutch 105, and a hand-operated brake 106, the brake being manipulated by the operator when the load on the tackle is lowered. By the use of this brake in the apparatus shown, the slab may be lowered by gravity by the 125 operator handling the brake to regulate the speed with which the slab descends, and he can likewise at will stop the descent of the slab.

In the operation of the apparatus in sub- 130

aqueous work on slopes and in deep water, the reinforced concrete slab or covering may be constructed upon the forming-barge either before it is warped into place between the two floats or platforms, of the catamaran, or after the barge has been moved in between these platforms. When the forming-barge is in place with the finished slab thereon, the hooks of the hoisting-tack are connected with the suspending eyes or rings on the slab, and the engine is started so as to lift the slab sufficiently from the barge to withdraw it from beneath the slab. The tackle is then operated to lower the slab as hereinbefore described and the same is deposited on the ground at a point below the space between the floats, which has been previously occupied by the forming-barge. When the slab is on the ground, each of the hooks is detached and the hoisting-tackle is thereby released and is then raised above the level of the forming-barge. The apparatus is then moved either in a fore or aft direction or sideways so as to lay another slab adjacent to the first one, and the operation is then repeated. As the means for supporting the slab from below and the slab hoisting mechanism may be moved relatively to each other in the horizontal when the slab is to be lowered into its position of rest, either the said support may be so moved horizontally after the slab is slightly lifted and suspended, or the said support may be held at rest and the slab be lifted and the support cleared by a horizontal movement of said hoist.

A set of forming-barges may be operated in conjunction with the single catamaran apparatus herein described, and by the use of this apparatus, I propose to lay reinforced sub-aqueous concrete slabs of a very large size, say forty feet by one hundred feet, and about four inches thick; the apparatus being constructed of sufficient strength to handle slabs of this size and weight, which latter in some cases might reach two hundred tons. Where the slabs are laid in set or hardened condition, they may be made at a distant point and brought to the catamaran on barges, which in turn may be warped in between the floats.

When it is desired to inspect a slab after it has remained on the water-bed for some length of time, this may be readily done by leaving the tackle connected with the deposited slab until the desired time to raise it, and this affords a convenient facility for such inspection. The raised slab may then be re-deposited in its place and the tackle disconnected therefrom. This is an important advantage in sub-aqueous work.

An important feature of the construction herewith shown is that of the tie or spacing rods which are connected between each tackle in two directions at right angles to

each other, and which serve to prevent any sag or tendency to pull together the points of suspension at the anchor bolts by the bending of the slab due to its great weight, and these rods also act to resist strain. This is of especial importance where the slab is deposited more than once, as in the case where a slab is to be inspected after once having been deposited, and also in the laying of concrete slabs in green, plastic form before they are hardened.

To lay the slabs on a sloping embankment under water involves conditions more complex than merely lowering the slabs from a barge, floating on the surface, to the river-bed whose plane is substantially parallel to the water surface.

It is important to note that a machine capable of performing the sub-aqueous work herein referred to must be practically stable and the centre of gravity must be held practically in the line of stable equilibrium, as in the construction herewith shown, and as will be understood from the cross-section of the apparatus in Fig. 6. In this apparatus the metric centre is always above the centre of gravity and these two centres are in the same vertical plane, and this is an important result. In handling sub-aqueous slabs of large area and great weight, the centre of gravity and line of stable equilibrium can be held in the transverse and longitudinal position by shifting the load so as to balance it by means of the movable barge on which the slab is placed.

This apparatus is especially adapted to lay protective coverings or slabs on water-beds or embankments to protect the same against erosion, and it is particularly adapted for river embankments of the character found to exist on the Mississippi River. The apparatus may also be used for foundation work where large areas of grillage are sunk by a super-imposed layer or slab of concrete, the grillage serving as a cradle and as part of the foundation; and also for constructing sub-aqueous floors in break-water construction in deep water, as well as covering large areas of sub-aqueous surfaces in shallow water from the embankment down and out in the deep water.

I wish to be understood as not limiting my invention to the particular structures herewith set forth as various modifications may be made in the different parts thereof, without departing from the spirit of my invention.

Having thus described my invention, what I claim is:

1. In apparatus for laying slabs on the surface to be protected, floats spaced apart with an unobstructed water space between them, a movable slab support capable of being moved horizontally into and out of the space between said floats, hoisting tackle

mounted on said floats for engaging and lifting a slab from said support clear of the same when the support is to be withdrawn, said hoisting tackle being constructed and 5 arranged to lower one end of the engaged slab at greater speed than the other and thereby cause the slab to be lowered out of the horizontal to its position of rest.

2. In apparatus for laying protective 10 slabs on the surface to be protected, the combination of two platforms arranged in substantial parallel relation opposite each other with the space between them open at the 15 respective ends, a super-structure mounted above said platforms and over the space between them, hoisting mechanism for the slab mounted on said super-structure, and a slab carrying barge adapted to be warped in between said platforms and withdrawn there- 20 from at either end.

3. In apparatus for laying protective slabs on the surface to be protected, the combination of two platforms arranged in substantial parallel relation opposite each other 25 with the space between them open at the respective ends, a super-structure mounted above said platforms and over the space between them, hoisting mechanism for the slab mounted on said super-structure, and a slab 30 carrying barge adapted to be warped in between said platforms and to be withdrawn therefrom at either end, the said super-structure projecting beyond one end of said platforms so as to overhang the space be- 35 tween the platforms at such end.

4. In apparatus for laying slabs on the 40 surface to be protected, a pair of permanently spaced apart floats and a super-structure between the same, hoisting tackle mounted on said superstructure above said

space, a horizontally movable slab support which can be moved into and out of the space between said floats to permit vertical lowering of a slab by said hoisting tackle.

5. In apparatus for laying slabs on the 45 surface to be protected, a pair of floats spaced apart and having a tackle supporting structure mounted on said floats and bridging the space therebetween and serving to maintain the floats in spaced apart 50 relation, hoisting tackle mounted on said structure, and a slab supporting barge adapted to be entered and withdrawn in said space between the floats.

6. In apparatus for laying slabs on the 55 surface to be protected, a pair of floats arranged side-by-side in suitably spaced apart relation, a super-structure mounted on each float and spanning the space between them, said structure being provided at one end 60 with an extension overhanging the ends of the floats and adapted to extend and be disposed up a bank, a movable slab supporting barge adapted to be moved into and out of the space between the floats, and hoisting 65 tackle arranged on said superstructure for suspending the slab over said space and up a bank.

7. The method of laying revetment slabs, which consists in maintaining a pair of 70 floats in spaced apart relation side-by-side, supporting the slab on a barge entered between said floats, then hoisting said slab bodily from the barge, then withdrawing the barge from between the floats, and then 75 lowering the suspended slab to position of rest.

In testimony whereof, I have hereunto set my hand.

ALEXANDER CRAWFORD CHENOWETH.
